UNITED STATES PATENT OFFICE.

LIONEL WILD, OF UPPER NORWOOD, ENGLAND.

MEANS FOR SPOTTING FABRICS IN ONE OR MORE COLORS.

1,087,859.

Specification of Letters Patent.

Patented Feb. 17, 1914.

Application filed August 24, 1912. Serial No. 716,903.

To all whom it may concern:

Be it known that I, LIONEL WILD, a subject of the King of Great Britain, residing at 160 Beulah Hill, Upper Norwood, in the 5 county of Surrey, England, have invented certain new and useful Improvements in and Relating to Means for Spotting Fabrics in One or More Colors, of which the following is a specification.

10 This invention relates to means whereby it is possible to spot fabrics mechanically and with greater precision, in designs of various colors, combination of colors and also designs formed with alternate spots of various 15 colors.

Heretofore it has only been possible to spot perfectly in one color; that is to say, by the present known means there is a tendency when producing designs in more than 20 one color for the distance between the spots of the various colors to be irregular consequently destroying the effect of the design, and the object of this invention is to overcome or minimize these defects, and this is 25 achieved by the employment of a multiple frame to be described hereinafter.

In the accompanying drawings:—Figure 1, is an end view of that portion of a machine which is necessary to illustrate this invention. Fig. 2, shows a set of frames assembled for printing in two colors. Fig. 3, is a sectional view of the preceding figure. Fig. 4, is a plan view of Fig. 2, and Fig. 5 is a side elevation of one of the trays.

35 In Figs. 2 and 3, a small number of pins, or other suitable color-applying devices used for spotting are shown in position.

One form of machine used in connection with this invention consists of a traveling carriage *a*, capable of carrying a frame *b*, on which the fabric to be spotted is stretched and held in position. The carriage *a*, passes under a framework *c*, in which slides vertically a frame *d*. On this frame *d*, are 40 mounted guides *e*, to carry the design frames, the frames being adjustable, and when adjusted locked in position. Rails *f* are also provided to carry the trays containing the solutions from which the spots are 45 formed. The inner surface of the solution trays on which the points of the pins rest when immersed are perfectly level so as to insure the spots being of a uniform size.

50 Lifting means comprising cords and pulley, or other mechanical means, such as *g*

and *h*, are provided for raising and lowering the frames for the various operations.

The plates on which the designs are formed by means of perforations are perforated simultaneously, or in such a manner 60 that the perforations in each plate are exactly over one another when assembled. When printing in two colors, three plates 1, 1, and 2, are employed, attached respectively to individual frames 3, 4, and 5. Two of 65 these frames 3, 4, and the plates 1, 1, carrying the design are secured together as shown with such a distance between them as will insure the pins being vertical and prevent lateral movement of the same. These two 70 frames are termed the lower frame. The third or upper frame 5, and its plate 2, is independent of the lower frame but is contained within or above the frame 3.

The pins *i*, for printing in one of the two 75 colors are passed through the perforations in the two lower plates 1, 1, and are suspended by their heads on the upper of the two lower plates. The perforations of that part of the 80 design which it is desired to print or spot in the other color are left vacant in the two lower plates 1, 1, and longer pins *j*, pass through the upper or third plate 2, and into those perforations left vacant in the lower plates 1, 1. 85

The plate *m*, is sufficiently heavy that when the frame 5, is lowered it forces the pins down so that the points of the pins shall rest on the bottom of the tray 6 containing the solution.

90 The spotting or printing is accomplished in the following manner:—The third or upper frame 5, is raised and locked in position by the catch *k*, engaging the upper surface of the crossbar *l*, this allowing the pins *i*, 95 in the two lower plates 1, 1, to enter the spotting solution in the tray 6 when lowered, but not those contained in the upper frame 5. The pins *i*, touch the bottom of the tray, thus insuring an equal quantity of solution being 100 picked up by each pin, even should the pins be of slightly different lengths. As long as the shortest pin touches the bottom of the solution tray the spots will be of uniform size. The frames are then raised collectively by 105 the cords *g*, the tray containing the solution drawn away, and the solution taken up by the pins drops on to the material which has been placed beneath, forming the spots. The upper frame 5, is now disengaged, and low- 110

ered into the position shown in Figs. 2, and 3. A tray 6 containing a solution of another color is passed underneath and the frames lowered collectively, the lower frame 5 engaging stops 7 on the side of this tray preventing the shorter pins *i*, from entering the solution, the longer pins *j*; that is, those in the top plate, entering the bath of color. The frames are now raised, the bath drawn 10 away, and the spotting takes place as in the previous case. During the first spotting operation, *i. e.*, when the shorter pins *i* are used, the tray employed is identical with that shown in Fig. 5 with the exception that it 15 lacks the afore-mentioned stops 7. Illustration of this first tray is, therefore, considered unnecessary.

To insure greater precision in the spotting of the second color the points of the 20 pins which are suspended from the third or upper frame are raised to the same level as those in the lower frame so that when the operation of spotting takes place the solution taken up by all the pins shall drop approximately the same distance. This refers 25 to spots of sufficient size to drop from the pins by their own weight. If it is necessary to produce a smaller spot the frames would be lowered until the pins touch the 30 material and should it be necessary, steam would be applied under the fabric to facilitate the spots leaving the pins.

The position of the pins shown in Fig. 1, is that when the pins *j*, are immersed 35 in the bath or tray containing the solution.

When it is desired to print or spot in three or more colors additional frames are provided each carrying pins of greater length, similar or independent additional raising 40 apparatus only being required, the method of working being still the same.

The baths containing the spotting solutions may be divided and sub-divided and each compartment contains a separate color.

45 When one section has been spotted the carriage *a*, carrying the frame on which the material is supported is moved and the next section spotted and so on until the whole length is printed or spotted.

50 It will be obvious that if it is desired to spot in one color only, this can be effected by lowering the upper frame so that the ends of the pins in all the frames are level and immersing all of them in the single 55 color and then spotting therefrom.

Having now particularly described and ascertained the nature of my said invention and in what manner the same is to be performed, I declare that what I claim is:

1. An apparatus for forming designs on 60 fabrics or the like composed of imitation beads or raised spots, in one or more colors, comprising a multiple frame, each frame carrying a plate on which the design is perforated and fitted with pins of various 65 lengths and means to operate the frames, substantially as described and illustrated by the accompanying drawings.

2. A device for forming designs on fabrics or the like in one or more colors, comprising 70 a multiple frame, each member of which carries a plate whereon the design is perforated, and is provided with color-applying devices of various lengths, means for raising and lowering said members collectively, and means for retaining a member in inoperative position during the latter movement of another member.

3. A device for forming designs on fabrics or the like in one or more colors, comprising 80 a multiple frame, each member of which carries a plate whereon the design is perforated, and is provided with color-applying devices of various lengths, means for raising and lowering said members collectively, means for retaining one of said members in inoperative position during one lowering movement of another member, and means for arresting the movement of another member when said members are again 90 lowered, to hold that member in inoperative position.

4. A device for forming designs on fabrics or the like in one or more colors, comprising 95 a frame having upper and lower members, each of which carries a plate whereon the design is perforated and is fitted with color-applying devices, means for raising and lowering said members collectively, and separate means for alternately holding said upper and lower members in inoperative position during two successive lowering movements.

In testimony whereof I have hereunto set my hand in presence of two subscribing witnesses.

LIONEL WILD.
